UNITED STATES PATENT OFFICE.

ALFRED STELZNER, OF WIESBADEN, PRUSSIA, GERMANY.

MOISTENING-PAD FOR ENVELOPES.

SPECIFICATION forming part of Letters Patent No. 483,634, dated August 5, 1890.

Application filed November 5, 1889. Serial No. 329,380. (No model.)

To all whom it may concern:

Be it known that I, ALFRED STELZNER, of Wiesbaden, Prussia, German Empire, have invented an Improved Moistening-Pad for Envelopes, of which the following is a specification.

This invention relates to a pad for moistening the gummed flap of an envelope, thus avoiding the necessity of licking such flap.

10 The invention consists in the various features of improvement more fully pointed out in the claims.

In the accompanying drawings, Figure 1 is a sectional end view of my improved moistening-pad; Fig. 2, a plan thereof; Fig. 3, a plan of a modification; Fig. 4, a section on line xx , Fig. 3; and Fig. 5 a perspective view showing the apparatus in use.

The letter A represents a shallow tin box, 20 inclosing a piece of felt, cloth, or similar article B and closed by a cover C. This cover is partially cut out, as at D, so that the felt B is exposed. The cut-out portion represents in shape two long rectangles joined at an ob-

25 tuse angle. E are additional spaces cut out of cover C, each of such spaces having the shape and size of a postage-stamp.

To the cover C there is secured a pair of 30 knobs F, which are grasped by the thumb and middle finger of the left hand while the flap

of an envelope is pressed upon the felt by the index finger of the same hand, as shown in Fig. 5.

In Fig. 3 the spaces E are dispensed with, 35 and in lieu of the cut-out space D a larger space G is cut out of the size substantially as the entire flap of an envelope.

The box A and cover C may be varnished, bronzed, or otherwise ornamented or pro- 40 tected.

In use the pad B is moistened and the apparatus is placed between the body and flap of an envelope, as in Fig. 5, to moisten the latter.

45 For moistening postage-stamps they are placed upon the cut-out spaces E.

What I claim is—

1. The combination of box A with pad B, cut-out cover C, and knob F, substantially as 50 specified.

2. The combination of box A with pad B, cover C, having the cut-out parts D E, and knob F, substantially as specified.

55 In testimony whereof I hereunto sign my name, in the presence of two subscribing witnesses, this 15th day of October, 1889.

ALFRED STELZNER.
